ATTACHMENT FOR BULLDOZER BLADES

Thomas W. Von Carnop, Fall City, Wash.

Application October 7, 1946, Serial No. 701,718

2 Claims. (Cl. 214—140)

1

My present invention relates to the art of earth moving machines and, more particularly to an attachment for bulldozer blades.

There are many forms of excavation still being done by relative crude means, very often hand labor being resorted to. This is occasioned by the fact that we have in general usage two types of earth-moving equipment, one with an adjustable blade which actually pushes the earth along the surface of the ground. This type is represented by the bulldozer and the various forms of adjustable blade scrapers. The second type of equipment is distinctly a carrying operation. Originally the wheeled scraper was used for this purpose, but this has been largely supplanted by the various forms of carryalls and the like, which of themselves pick up dirt after the order of the old horse-drawn wheeled scraper, and can be used to transport the same for considerable distances.

In between these two forms of earth moving equipment there is a specific need for equipment that can be used to dig material and to pick up the same and carry it, or to carry material that of necessity has been loosened by a heavy bulldozer blade or scarifier. My invention falls in this third group of earth moving machines.

My attachment for bulldozers provides an auxiliary digging blade with supporting end walls, but uses the mold board of the bulldozer as a backing member for the substantially horizontal cutting blade. Means are further provided for holding my attachment in operating position and then for selectively dumping the same.

The principal object of my present invention is, therefore, to provide an attachment for bulldozers which will extend their field of operation and permit them to work in very restricted places and to be able to carry out of such places material loosened therein.

A further object of my invention is to provide, as a single unit, an attachment that can be quickly and securely applied to a standard bulldozer which will greatly increase its usefulness.

A further object of my present invention is to provide an earth carrying means for use in conjunction with a bulldozer which provides in effect a dumpable bucket mounted on the lower portion of the bulldozer moldboard so that material loaded therein will dump by gravity when the restraining means is released.

A further object of my present invention is to provide means whereby a bulldozer working in a narrow cut can load material and back out with the same and, if desired to spread the same evenly over a surface, this can be achieved.

2

A further object of my present invention is to provide means whereby material can be picked up in one part of a tract of ground, transported to another and there spread out evenly over the ground.

A further object of my present invention is to provide restraining and securing means for my dumpable bucket which can be easily secured to a bulldozer blade and which will not affect its workability when the bucket arrangement is disconnected from the bulldozer.

A further object of my present invention is to have a unit which, acting in operation with the moldboard of the bulldozer, will provide means for carrying materials of considerable weight from one point to another, or lower them from a height to the ground level or to pick them up from the ground level and raise them a reasonable height.

Further objects, advantages and capabilities 20 will be apparent from the description and the disclosure in the drawings or may be comprehended or are inherent in the device. In the drawings:

Fig. 1 is a perspective view showing my attachment in full line perspective with a conventional type of suitable bulldozer for use therewith, shown in dashed and dotted lines;

Fig. 2 is a side elevation showing my earth carrying attachment in its dumping position;

Fig. 3 is a side elevation showing my earth carrying attachment for bulldozers in its locked position ready for use;

Fig. 4 is a perspective view from the point of view taken from a rear side position showing all the elements making up my bulldozer attachment;

Fig. 5 is a vertical, cross-sectional view through my attachment and showing a bulldozer blade in dashed line relief; and

Fig. 6 is a fragmentary view in elevation showing a special digging tooth adapted for use with my device.

Referring to the drawings throughout which like reference characters indicate like parts, the numeral 10 designates the main or bottom plate 45 of my device. This I prefer to form with a sharpened working edge, as 11, and to bend the metal back on itself as indicated at 12, so as to give real strength and rigidity to the plate and to give it adequate strength for penetration into firm ground. This construction is probably best illustrated in Figure 5, where it will be noted that the entire plate is shown together with its point, as though made from a single piece of material. This is a desirable form of construction. However, if it is desirable from the standpoint of

economy in material, the beveled pointed section, and as much more as necessary for strength, may be made of the better grade of steel, while the balance of plate 10 may be of cheaper steel which is still suitable for the service to be rendered.

Attention is invited to the fact that plate 10 is positioned substantially at the bottom of the mold board 14 of the bulldozer and extends forward in a plane substantially parallel to the plane of the bottom frame member of the bulldozer.

Secured to each end of plate 10 are end plates 16 and 17. These plates are secured, preferably by welding thereto, to the ends of plate 10 and the rearward extending edges of plates 16 and 17, as 19 and 20, respectively, are curved so as to fit snugly into the curved face of the bulldozer blade or moldboard 14. In order to give rigidity to the structure, I provide inwardly extending plates or angle members 22 and 23 secured substantially normal or at right angles to plates 16 and 17 respectively, and to be further secured to the inner edge 25 of plate 10, as by welding thereto.

Secured to the back of plates 22 and 23 I provide stiffeners 27 and 28. These are preferably welded to plates 22 and 23 and have their back surfaces or edges, 29 and 30 respectively, curved similarly to the curved edges 19 and 20 of plates 16 and 17, so that they too will come into snug engagement with the mold board of the bulldozer.

With the arrangement as described, it will be noted that abutment against the moldboard of the bulldozer by my device is secured by the edges of the plates, namely the edges 19 and 20 of plates 16 and 17, the edges 29 and 30 of plates 27 and 28, and the edge 25 of plate 10. When so arranged, it has been found that packing of soil or materials behind my unit and between it and the moldboard of the bulldozer will be cut through by the high pressure per unit area of the limited surfaces provided by these plate edges, so that we will at all times have a metal-to-metal bearing and the seating of the device in its operating position can be easily effected, even though the soil conditions under which the machine is operating would normally tend to pack considerably and prevent this snug engagement were it not for the reduction of area provided by the plate edges.

In order to position my attachment firmly in operable position on the bulldozer blade, or moldboard, I provide end mounting plates 31 and 32. These are adapted to be secured, as by a plurality of bolts 34, to the end plate 36 of the bulldozer blade assembly. Plates 31 and 32 carry journals to accept the pivot pins 38 which normally are secured to end plates 16 and 17 of my attachment and extend through plates 31 and 32 and are secured in rotatable bearings therein and locked in place by suitable washers and nuts.

In order to selectively secure my attachment in operating position on the bulldozer blade assembly, I provide end bearing members 40 and 41, and central bearing members 42 and 43, all of which serve as journals for rod 45. These brackets may be secured to the bulldozer in any desired manner although it has been found generally most convenient to merely weld the same in place. Shaft 45 has fixedly secured to it latch members 47 and 48. These members are provided with the plate engaging faces 50, which are formed as part of a hook arrangement on each of the outboard ends of members 47 and 48. These faces are adapted to engage plates 22 and 23 of my attachment.

At their opposite ends, latch members 47 and 48 are provided with spring centering means at

52, so as to hold in operating position springs 53, which in turn rest on the side bars of the bulldozer assembly. These springs normally urge the latch members into the locked position. Fixedly secured to shaft 45 is the operating or trip lever 55, and secured to lever 55 may be any convenient means for operating the same. In some instances, a rod or bar may be employed, or on machines so equipped, air or hydraulic cylinders might be employed to operate the latch means. However, generally a simple rope, as 56, attached thereto and led back to the operator's seat is sufficient for a successful operation of my device.

Method of operation

15 My device can be most satisfactorily used under those conditions where it is so difficult to use the existing or conventional equipment. This particularly relates to digging foundations, digging 20 out basements under buildings that have already been constructed, and in many other types of work where it is necessary to head the machine into the work space, load it, and back it out with its load. While my machine will work under 25 many other conditions, this is a particularly satisfying use.

Normally my device is secured to the ordinary bulldozer blade assembly, by securing end plates 31 and 32 in place by bolts 34, then securing the 30 various brackets as 41, 42, 43, 40 in place on top of the moldboard supporting means of the bulldozer. In this position, my entire assembly is handled by the normal elevating and supporting means employed with the bulldozer for its normal 35 operation.

Where the materials are sufficiently loosened, and my device with latches 50 in their locked position appears as shown in Figures 1, 3 and 5, the machine is advanced and a load of material 40 is scooped up on plate 10. The end plates 16 and 17 prevent spillage off the end of the plate and the moldboard of the bulldozer supplies the backing plate for the material thus collected.

Normally, after the bucket has been filled, the 45 tractor is backed away and the bucket may be elevated so that the supporting arms of the bulldozer assume the position of Figure 2, and under such conditions, considerable load can be carried without spillage. The load can now be dumped by pulling on rope 56 and the entire load deposited at one point. If it is desirable, my loaded 50 bucket may be lowered to the ground and tripped. The operator may then, by backing the tractor, spread the material out over a long swath. In 55 this way a thin coating of the material can be spread in uniform thickness. This spreading operation is very useful in grading or applying surfacing to acreage or roadways, and the like. This operation can spread material uniformly over distances several times as great as a blade 60 scraper or the back spreading of a bulldozer.

To relatch my bucket after dumping, the bulldozer blade is lowered until edge 11 of my bucket 65 engages the ground, at which time my bucket is revolved about pivot 38 until the cam surfaces 58 of latches 47 and 48 engage plates 22 and 23. This action forces the latches up and then springs 53 complete the latching operation, as shown in Figures 1, 3 and 5.

70 Referring to Figure 6, I have illustrated a form of tooth that has been found very desirable in digging into impacted or otherwise semi-solidified material which the bulldozer does not have sufficient power to drive the wide blade into. Under such conditions, I prefer to employ a

plurality of teeth extending out beyond the normal edge 11, so that the same energy or pressure may be exerted by the bulldozer, but on a much reduced area, so that greater penetration and breaking up of the hard materials can be achieved. To be of practical value, such a device must be capable of being quickly installed and removed from the device, and to this end, I have provided the principal securing means in a tapered wedge 60, of which a sufficient number are to be employed so as to hold my auxiliary teeth in their adjusted position of use. As an aid in centering these wedges, effecting easy alignment of their multiplicity of holes, and preventing vibration, I provide securing bolts, as 62. The width of teeth 64 should be a matter designed in keeping with the type of material with which they are to be used, and while they may be formed as a plurality of separate teeth, I prefer in many cases to have the lower connecting bar 65 extend for the full width of bottom 10.

In addition to providing less frontal surface in contact with hard material it will be noted that the slope of surface 66 is much more gradual than the normal surface of edge 11, and this too has been found to be of material assistance in penetrating firm or semi-solid material.

It will be clearly apparent, it is believed, from the above description and the disclosure in the drawings that my invention comprehends a novel construction of a bulldozer attachment or bucket that is simple and positive in operation. Further, it is simple in construction and makes maximum use of the existing bulldozer parts to the end that it may be cheaply constructed, even though it greatly increases the usefulness of the bulldozer itself.

Having thus described my invention, I claim:

1. A material moving device for use with a bulldozer having a moldboard consisting of: a material moving blade disposed in front of the lower edge of the bulldozer moldboard; end walls secured to each end of said blade and curved adjacent the moldboard to fit the same; straight plates secured normally to said end walls and

5
10

to said blade and resting on said moldboard only at the plate ends; stiffeners secured normally to said plates and curved on their free edge to fit said moldboard; attachment plates secured to the bulldozer; pivot means between said end walls and said attachment plates disposed in front of and near the bottom of said moldboard; latch means adapted to secure said blade in a substantially horizontal plane and means for releasing said latch means and permitting the dumping of the material moving device.

2. A material moving device for use with a bulldozer having a moldboard, consisting of: a material moving bucket having a blade disposed in front of the lower edge of the bulldozer moldboard; end walls secured to each end of said blade and adapted to rest on the moldboard; straight plates secured normally to said end walls and to said blade and resting on said moldboard only at the plate ends; reinforcing means adapted to stiffen said bucket and to fit said moldboard; attachment plates secured to the bulldozer; pivot means between said end walls and said attachment plates disposed in front of and near the bottom of said moldboard; spring urged latch means coacting with said straight plates adapted to secure said blade in a substantially horizontal plane and means for releasing said latch means.

THOMAS W. VON CARNOP.
